FIG. 3

FIG. 1 is a front perspective view of a sofa incorporating the features of my new design.

FIG. 2 is a perspective view of the sofa of FIG. 1 as viewed toward the rear and left-hand side thereof.

FIG. 3 is an enlarged fragmentary view showing one of the joints and the screw heads in greater detail.

The end of the sofa not shown is a mirror image of the side shown.

I claim:

The ornamental design for a sofa, as shown and described.
